UNITED STATES PATENT OFFICE.

JOHN A. HARRISS, OF NEW YORK, N. Y.

KNIFE.

1,047,629.

Specification of Letters Patent.

Patented Dec. 17, 1912.

Application filed August 17, 1911. Serial No. 644,551.

To all whom it may concern:

Be it known that I, JOHN A. HARRISS, a citizen of the United States, and a resident of the city of New York, borough of Manhattan, in the county and State of New York, have invented a new and Improved Knife, of which the following is a full, clear, and exact description.

My invention relates to knives and it has for its object to provide one having a detachable blade, which is held against the handle by a hook rod, the hook on the rod engaging the blade around an orifice, and the rod being secured in a channel in the handle. The blade is reinforced by a brace bar, the butt end of which is disposed in a socket in the handle.

Additional objects of the invention will appear in the following complete specification, in which the preferred form of the invention is disclosed.

In the drawings similar characters of reference indicate corresponding parts in all the views, in which—

Figure 1 is a perspective view of the invention; Fig. 2 is a side elevation partially in section; Fig. 3 is a sectional view on the line 3—3 of Fig. 2; Fig. 4 is a sectional view on the line 4—4 of Fig. 2; and Fig. 5 is a view showing the securing rod.

By referring to the drawings, it will be seen that the handle 5 has a longitudinal channel 6, extending therethrough, and spaced from the said longitudinal channel there is a socket 7, in one end of the handle 5. A ferrule 8 is disposed around the said end of the handle 5, forming one edge of the socket 7, the opposite edge 9 of the said socket being formed by a metal member which is disposed in the handle 5. The blade 10 has a recess 11, on its back edge 12, and near its point 13, to receive a transverse pin 14 secured to the sides of the U-shaped brace bar 15. This brace bar 15 is disposed over the back edge of the blade 10, with its pin 14 disposed in the recess 11. The butt end 16 of the U-shaped brace bar is disposed in the socket 7 so that when the butt end 17 of the blade 10 is disposed against the end of the handle 5, with the U-shaped brace bar 15 in position, the butt end 16 of the brace bar will be disposed against the inner end of the socket 7, with the pin 14 on the brace bar disposed firmly against the forward wall of the recess 11. In this way the

brace bar will be held firmly in position relatively to the blade 10 and to the handle 5.

There is an orifice 18 in the blade 10, near its butt end, the hook 19 on the securing rod 20 engaging the said orifice and the rod 20 being disposed in the channel 6, so that the nut 21 may engage the threaded terminal 22 of the rod 20 to draw the rod 20 back and with it the blade 10, until the blade 10 is held firmly against the end of the handle 5, with the brace bar 15 held firmly between the inner end of the socket 7 and the recess 11. When the nut 21 is turned home it will be found that the blade is held firmly in position against the handle, and that the brace bar 15 is secured in position by the said operation.

It will be noticed that the brace 15 embraces the back of the blade 10 throughout the major portion of its length, interlocks with such blade near its forward end and projects at its rear end beyond the blade to enter the recess in the end of the handle. This rear extension of the brace co-operates with the rod 20 in securing the blade firmly to and bracing it in connection with the handle. In operation, by loosening the nut 21, the handle, blade, rod 20 and brace 15 can be quickly detached from each other, leaving the parts in convenient position for sterilization or other cleansing or for the substitution of a new blade 10, as may be desired.

Having thus described my invention, I claim as new, and desire to secure by Letters Patent:

1. A knife comprising a handle having a ferrule around one end, there being a socket in the said end and a channel in the handle extending through the said end, a blade having a recess remote from its butt end, and a brace bar detachably engaging the blade with its butt end disposed in the socket, and having a member normally disposed in the recess, and a rod having a hook detachably engaging the blade and secured in the channel.

2. A knife comprising a handle having a socket in one end, a blade having a recess, a brace bar engaging the blade and having a member disposed in the recess, and a butt end disposed in the socket, the distance between the member on the brace bar and the butt end of the brace bar being greater than the distance between the outer portion of

the forward wall of the recess and the inner end of the socket, when the blade is in position in the handle, and means for holding the blade in the direction of the handle 5 for securing the blade in place, and the brace bar in position relatively to the blade and the handle.

3. A knife comprising a handle having a socket in one end and a channel extending 10 through the said end, a blade having a recess remote from its butt end, a brace bar engaging the blade and having a member disposed in the said recess, and a butt end disposed in the socket, the distance between 15 the member on the brace bar and the butt end of the brace bar being greater than the distance between the outer portion of the forward wall of the recess and the inner end of the socket when the blade is in position 20 in the handle, and a securing rod having a hook for engaging the blade, the rod being secured on the channel for holding the blade in the direction of the handle and the brace bar in position relatively to the blade and 25 the handle.

4. A knife comprising a handle having a channel formed longitudinally through it for the passage of a blade fastening bolt, the handle being also provided in the blade end 30 with a socket, a blade, a brace bar fitted longitudinally to the back edge of the blade and engaged at its outer end, with the blade and projecting at its butt end beyond the blade to enter the socket in the handle, the 35 butt end of the blade bearing against the end of the handle, and a securing rod hooked at one end in connection with the blade, and passing through the longitudinal channel in the handle and secured substantially as set forth.

5. A knife comprising a handle having a socket in one end and a channel extending through the said end, a blade having a butt end disposed against the said end of the 45 handle, a recess spaced from the said butt end, and an orifice, a brace bar detachably engaging the blade with its butt end dis-

posed in the socket and having a member normally disposed in a recess in the blade, and a rod having a hook detachably engag- 50 ing the orifice in the blade and secured in the channel.

6. A knife comprising a handle having a socket at one end, and a channel extending through the said end, a blade having a butt 55 end disposed against the said end of the handle, a recess spaced from the said butt end, and an orifice, a brace bar fitted longitudinally to the back edge of the blade, and detachably engaging the blade, the butt end 60 of the brace bar being disposed in the socket, and a rod having a hook detachably engag- ing the orifice in the blade and secured in the channel.

7. A knife, substantially as herein de- 65 scribed, comprising a handle having in its blade end a longitudinal socket and also having a longitudinal opening for a securing rod, a blade abutting at its rear edge against the socketed end of the handle, a 70 brace bar fitted to the back edge of the blade and engaged therewith and projecting beyond the butt end of the blade and entering the socket in the handle and a se- 75 curing rod connected with the blade and extending thence into the longitudinal opening of the handle and secured, all substan- tially as and for the purposes set forth.

8. A knife, substantially as described, comprising a blade, a brace bar fitted to the 80 back edge of the blade and projecting be- 85 yond the butt end of the blade forming a rearward extension of the brace bar, a han- dle receiving said extension of the brace bar and means coöperating with such extension of the brace bar in securing the blade to the handle, substantially as set forth.

In testimony whereof I have signed my name to this specification in the presence of two subscribing witnesses.

JOHN A. HARRISS.
